FOREIGN PATENT DOCUMENTS

WO 2011001312 A 1/2011

Primary Examiner — Ricky Pham*(74) Attorney, Agent, or Firm* — Alexander D. Raring**CLAIM**

The ornamental design for an immersion mixer with trigger manipulable from multiple grasping locations, as shown and described.

DESCRIPTION

FIG. 1 is a perspective view as seen from the right and front sides of an immersion mixer showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Broken lines in the drawings depict portions of the immersion mixer that form no part of the claimed design.
